LABELING MACHINE

Robert John Newman, Enfield, and Dagobert Siegfried Freund, London, England, assignors of one-third to Edward Albert Baker, London, England

Application May 9, 1945, Serial No. 592,856
In Great Britain May 19, 1944

2 Claims. (Cl. 216—54)

1

This invention relates to labelling machines and particularly to machines for applying labels to packages and containers such as glass bottles and has for its chief object the provision of an improved form of such a machine which is of rigid and inexpensive construction and is especially suitable for applying labels to glass bottles and like containers of the small variety.

In accordance with the invention there is provided an improved form of labelling machine comprising a pair of gum plates or pickers mounted for reciprocating movement e. g. in a horizontal plane, and adapted after picking-up or collecting a label from a pile to bring the same into a transfer position in which the label may be applied to the package or container as, for example, by relative movement, transversely of the reciprocating movement, between the package and the label.

In order that the said invention may be clearly understood and readily carried into effect, the same will now be more fully described with reference to the accompanying drawings, in which:

Fig. 1 is a side view, partly in section, of one form of the machine produced according to the invention;

Fig. 2 is a plan view of the machine shown in Fig. 1; and

Fig. 3 is a front view of the said machine.

In the form of the invention illustrated in the accompanying drawings, the machine is shown comprising a framework 1 provided at the upper part thereof with a gumming or adhesive applying device *a*, a label pile *b* and a label applying means disposed on the side of the label pile opposite that on which the adhesive applying device is located.

The gumming or adhesive applying device may be of any suitable form and is here shown as comprising a gum- or adhesive-containing trough 1 having a positively driven gum-pick roller 2 rotatably mounted therein with its peripheral surface dipping into the adhesive and engaging with the surface of a freely-mounted transfer roller 3. The latter engages with another transfer roller 4 of smaller diameter and the gum or adhesive-applying roller 5 is arranged and mounted to receive the adhesive from the roller 4 and to apply the same in the form of a thin, evenly spread coating to the gum plates or pickers which, as is hereinafter described, are presented to or brought into contact with the lower part of the roller 5 where it projects downwardly through an opening 6 formed in a part of the trough 1 which is partitioned off from the adhesive-containing part thereof. The pick-up roller 2 may be driven in any suitable manner and is shown mounted on a spindle provided at one end thereof with a sprocket wheel 7 adapted to be rotated continuously by a sprocket chain 7a which extends around the

2

sprocket wheels 7b and 7c, the latter being mounted in position on the main driving shaft B.

Adjacent one end of the trough 1, viz. the right hand end as shown in Fig. 1, there is arranged the pile *b* of the labels to be applied. Such labels are contained in a label box 8 which is open at its lower end and the labels are arranged therein in superposed relation with their faces uppermost. The label box may be slidably mounted in vertical guides 9 and is adapted to be raised and lowered, as hereinafter described, through a connection with a vertically disposed rod 10 having its lower end connected, e. g. by a pin and slot connection, with a lever 12 which is pivoted to the framework at 13 and is adapted periodically to be displaced about its pivot by a cam 15 on which a roller 16 on the lever rests.

On the side of the pile *b* opposite that on which the gumming device is located, there is arranged a cradle or support 20 for the package or container (shown in dotted lines at A) to be labelled. The said cradle or support is preferably mounted in position on the upper end of a vertically disposed rod 21 capable of being displaced longitudinally as, for example, by a lever 22 pivoted on the framework 1 at 23 and provided with a roller 24 bearing against a cam 25 disposed coaxially with the cam 15 and adapted to be driven synchronously therewith by the main driving shaft B.

Mounted for horizontal reciprocatory movements beneath the gum-applying device and the label pile is a structure or carriage provided with a pair of gum plates or pickers. Said structure or carriage is indicated at 30 and is mounted for movement on a pair of laterally spaced guides or guide rods 31 extending across the machine and suitably secured in position at their ends to the framework. At its forward end the structure 30 is provided with a pair of laterally spaced and forwardly-extending, horizontally-disposed rods 33 and 34 on which the picker or gum plates 35 and 36 are mounted so as to be capable of angular movement thereon. The picker or gum plates are mounted in position so that they normally lie in a horizontal or substantially horizontal plane and so that they extend across the machine and towards one another with their opposed side or front edges spaced from one another to provide a gap 40 therebetween, which gap, when the plates are moved into their extreme forward position, is located immediately above the package or container to be labelled.

The structure 30 carrying the gum plates or pickers is adapted to be moved back and forth so as to carry the gum plates from a position beneath the gum-applying device to a label-transfer position over the package or container to be labelled and back again and, for this purpose, the structure may be connected, as for example, by a pin-and-slot connection with the upper end

of a lever or arm 42 which is pivotally mounted in position on the framework at 43 and is provided with a roller 44 engaging with a further cam such as the cam 45 provided on the main driving shaft B. Such cam is formed so that the gum plates or pickers are caused to pause at least once during each forward movement as they pass from one limiting position, viz. the gumming position, to the other, viz. the label-transfer position, the arrangement being such that the pause is caused to occur as they arrive in a position beneath the label pile.

In operation, the gum plates or pickers are reciprocated so that they are caused to move from the extreme position shown in Fig. 1 to a position over the package or container to be labelled and back again. As they move forward from the position indicated in Fig. 1, they pass firstly under and in contact with the gumming or adhesive applying roller 5 so that their upper surfaces become coated with adhesive. Shortly thereafter they are brought into a position beneath the label pile b where they are caused to pause and while in this position the aforesaid open-ended label box 8 is, by the action of the cam 15 and rod 10, lowered in order to bring the underside of the lowermost label into contact with the upper and adhesively coated surfaces of the said picker plates. By the continued rotation of the cam 15, the label box is then raised clear of the picker plates leaving the lowermost label adhering to the latter which, by the continued rotation of the cam 45, are then caused to resume their forward movement which continues until the picker plates and the collected or adhering label arrive in the label-transfer position where that part of the label bridging the gap 40 will be disposed vertically over the package or container A to be labelled and the picker plates are again caused to dwell for a short period of time.

In the last mentioned position, the collected label is applied to the package or container by imparting to the latter a movement in a direction transverse to the plane of movement or reciprocation of the picker plates. For this purpose, the package or container may be raised, by the action of the cam 25 on the lever 22, so that it is caused to move upwardly through the gap 40 and, in so doing, to lift the label off the picker plates. As already mentioned, the latter are pivotally mounted in position on the rods 33 and 34. Preferably, the picker plates are normally yieldingly held in a horizontal or substantially horizontal position by suitable springs and, as the package or container moves upwardly into and through the gap 40, the picker plates will be tilted upwardly as shown by the dotted lines in Fig. 3, while the label is being drawn or slid off the picker plates and transferred to the package or container. In the preferred embodiment of the invention, means is provided for yieldingly holding the central portion of the label against the surface of the package or container as the latter rises and the transfer is effected. For this purpose, the machine may be provided with an upwardly extending guide 48 having slidably mounted therein a longitudinally or vertically displaceable rod 49 which is pressed downwardly by a spring 50 and is formed at its lower end with a pad 52, the arrangement being such that in the lowermost position of the rod the pad is disposed a short distance above the package or container and is free to rise in opposition to its spring as the container is raised. If desired, means may be provided for

cushioning the final stages of the upper movement of the container or for applying pressure to the label now in position on such container. For this purpose, a pair of pads 54 and 55 may be mounted in position as shown in Fig. 3 so that they are located one on each side of the pad 52 in a fixed position adjacent the end of the upward travel of the container.

We claim.

10. 1. A machine for applying labels to packages or containers, comprising a movable container support, means for reciprocating said container support, adhesive applying means, label transfer and applying means, a label pile interposed between said adhesive applying means and said label transfer and applying means, a label gumming and picker device, and means for reciprocating said gumming and picker device in a direction which is transverse to the direction of movement of said container support so that said gumming and picker device in moving toward said container support first receives adhesive from said adhesive applying means, and is then caused to collect a label from said pile and to bring said label to a container carried upon said container support, and means for timing the movement of said container support and said label transfer and applying means so that the label is transferred from the said label gumming and picker device to the container carried upon said container support during the movement of the said container support and container.
15. 2. A machine for applying labels to packages or containers, comprising a vertically movable container support, means for raising and lowering said container support, vertically movable label transfer and applying means set above said container support, adhesive-applying means, a vertically movable label-pile support interposed between said container support and said adhesive-applying means, means for raising and lowering said label pile support and a label pile carried thereon, at least one label-gumming and picker plate, means for moving said picker plate towards and away from said container support in a substantially horizontal plane, beneath said adhesive applying means and said label pile support, means for causing said plate to pause beneath said label pile so that when said pile support is lowered the lowermost label of said pile is brought into contact with the adhesive on said plate, and retained upon said plate when the lowered label pile is raised, and means for timing the movement of said plate in relation to the movement of said container support and said label transfer and applying means so that the label is transferred from the said label gumming and picker plate to a container carried by said container support during movement of said container support and container.
20. 35. 40.
25. 45.
30. 50.
35. 55.
40. 60.
